CARBURETOR GOVERNOR

Richard J. Brunner, Rochester, N.Y., assignor to General Motors Corporation, Detroit, Mich., a corporation of Delaware

Filed Oct. 23, 1957, Ser. No. 691,853
6 Claims. (Cl. 123—103)

The present invention relates to a charge forming device for an internal combustion engine in which governing means is provided for preventing excessive engine speeds. More specifically, this invention relates to a governing mechanism for a compound type carburetor, e.g. a carburetor having a plurality of induction passages and in which there is a correlation in the actuation of the throttle valves controlling the flow of combustible charge through the respective induction passages.

While governing mechanisms utilized in conjunction with carburetors are well known, it has proved particularly difficult to provide satisfactory governing mechanisms for controlling sequentially operating throttle valves in different induction passages. In compound type carburetors it is common to have at least one primary throttle and one secondary throttle and further which throttles are adapted to operate in sequence with the secondary throttle opening only after a predetermined amount of opening of the primary throttle.

The sequential operation of the throttles of a compound type carburetor may either be achieved mechanically by a mechanism of the type shown in Olson et al. 2,771,282 or automatically through a power servo mechanisms as shown in Braun 2,705,942. Each of the mechanisms for controlling sequential throttles presents its own difficulty. Copending application Serial No. 616,529, now Patent No. 2,862,487, granted December 2, 1958, discloses a governing mechanism for controlling mechanically coupled sequentially operating throttles of the type shown in the aforesaid Olson et al. patent.

The present invention is directed to a governing mechanism particularly adapted for use with a compound type carburetor employing a power actuated secondary throttle as illustrated in the Braun patent.

In the present device a carburetor is provided having primary and secondary induction passages which include throttle valves respectively disposed therein. The primary throttle is adapted to be opened in accordance with operator demand as manifested by accelerator pedal position. In addition, however, a governing device is connected to the primary throttle which permits the latter to be closed in the event engine speed exceeds a given value. A servo mechanism is connected to the secondary throttle and which servo mechanism is interconnected with the primary induction passage so that the actuation of the secondary throttle is determined by the air flow through the primary induction passage. Thus, as the engine speed increases beyond a desired value the governing mechanism is adapted to move the primary throttle in a closing direction which tends to reduce the air flow through the primary induction passage and in this way modifies the force tending to open the secondary throttle. It has, however, been found to be inadequate to govern the secondary throttle by modifying the force created by primary induction passage air flow to the extent this occurs in simply closing the primary throttle. It is found that by controlling the secondary throttle actuating vacuum force by primary throttle actuation alone causes the secondary throttle to hunt between an open and closed position resulting in erratic secondary throttle actuation.

Accordingly, in the present invention a venting mechanism is provided for operation in conjunction with the secondary throttle servo mechanism. The venting mechanism is controlled by the governing device in such a

2

way that when the speed of the engine exceeds a desired value atmospheric pressure is admitted to the secondary throttle servo causing that throttle to be moved to a closed position and avoiding indiscriminate hunting.

5 Other objects and advantages of the present invention will be apparent from a perusal of the detailed description which follows.

In the drawings:

10 FIGURE 1 is a partially sectioned view through a carburetor embodying the present invention;

FIGURE 2 is a partially sectioned view through the carburetor throttle body showing the throttle actuating mechanisms;

15 FIGURE 3 is a view along line 3—3 of FIGURE 2; and

FIGURE 4 is a diagrammatic representation of the governing mechanism utilized in the present system.

Referring to the drawings, a compound type carburetor is shown generally at 10. Carburetor 10 may be of the type shown in Patent Number 2,771,282 Olson et al. or any other well known type. The carburetor will be described in detail only insofar as is necessary to a proper understanding of the present invention.

20 Carburetor 10 includes primary and secondary induction passages 12 and 14 having venturi portions 16 and 18. As best seen in FIGURES 1 and 2, a lever 20 is connected to the primary throttle shaft 22. In order that a governing mechanism may be utilized in conjunction with the primary throttle 24, a spring 26 is fixed to one end of lever 20 so as to normally urge the throttle in an open direction. The opening movement of the primary throttle 24 is opposed or limited by an accelerator controlled lever 28 which includes a stop portion 30. As best seen in FIGURES 2 and 3 the adjustable stop 30 is adapted to coat with a corresponding stop member 32 formed on a lever 34 secured to the opposite end of primary throttle shaft 22. Thus while spring 26 urges the primary throttle in an open direction, the extent to which such opening may take place is limited by the accelerator controlled stop 30. In this way it may be seen that the primary throttle may be closed by a governing mechanism against the force of spring 26 without having to work against the force applied by the pressure exerted by the operator's foot.

40 45 A link or control rod 38 is fixed to the other end of primary throttle lever 20 and is adapted to be actuated by a servo device indicated generally at 40. Servo device 40 includes a pair of casing members 42 and 44 which peripherally clamp a diaphragm member 46 therebetween.

50 Diaphragm 46 includes a rod member 48 centrally fixed thereto and which member is articulated to control rod 38.

55 Casing 42 and diaphragm 46 form a chamber 50 which is suitably vented to the atmosphere. Diaphragm 46 and casing 44 form a chamber 52 adapted to be supplied with a vacuum force from a governing mechanism 54 which will be subsequently described. It is apparent that when the governor vacuum force reaches a given value it will overcome the throttle opening force of spring 26 and move the primary throttles 24 toward a closed position.

60 65 A lever 56 is fixed to the secondary throttle shaft 58 and has a control rod or link 60 articulated thereto. The other end of control rod 60 is articulated to a stud 62 centrally fixed to a diaphragm 64 of a secondary throttle actuating servo indicated generally at 66. Servo 66 includes a pair of casing members 68 and 70 adapted to peripherally clamp the diaphragm 64 therebetween. The chamber 72 defined by diaphragm 64 and casing 70 is open to the atmosphere. Chamber 74 defined by diaphragm 64 and casing 68 communicates through a conduit 76 with venturi 16 of the primary induction passage 12. A spring member 78 is disposed within chamber 74

and is adapted to bias the diaphragm 64 and stud 62 in a direction tending to close the secondary throttle 80.

After the primary throttle has reached a given degree of opening the air flow through primary venturi 16 will reach a sufficient value to create a vacuum force in conduit 76 which will overcome the spring 78 and move the diaphragm 64 to the left tending to open the secondary throttle 80 with a force which will be proportional to the velocity of primary induction passage air flow. The advantage of such a power actuated secondary throttle is that the degree of secondary throttle opening is not determined by operator demand but by engine demand. In other words, with mechanically coupled primary and secondary throttles it is possible for the secondary throttle to be opened in advance of the actual needs of the engine whereas with the subject device it is the engine's consumption of air which determines when the secondary induction passage will supply the additional air required for proper operation of the engine.

Insofar as the governing action of the primary throttles 24 is concerned, it is the same as that described in copending application S.N. 616,529 Olson, filed October 17, 1956. It is the governing of the secondary throttle that differs from the aforesaid copending application. Referring to governor servo 40, servo chamber 52 is communicated through a passage 82 and a conduit 84 to the carburetor induction passage posteriorly of the throttles so as to convey manifold vacuum to the chamber to assist in moving the diaphragm 46 in a throttle closing direction.

The speed responsive or governor mechanism 54 may be of the type shown and described in Patent 2,664,867 Hartzell et al., filed February 14, 1951, and does not, per se, constitute a part of the present invention. The speed responsive mechanism is pertinent to the subject invention only in combination with the subject unique throttle controlling devices. Insofar as the present invention is concerned it will suffice to say of the speed responsive device 54 that it includes a shaft 90 driven at engine speed through a gear 92 connected in turn with a member 94 on the engine cam shaft. Radially mounted on the shaft 90 is a centrifugal valve mechanism 96 biased by spring 98 in a position permitting spindle 100 to uncover port 102 admitting atmospheric air from an air cleaner conduit 104 to a passage 106 formed in shaft 90. Passage 106 in turn communicates at its other end with an annular chamber 108 in registry with a passage 110 connecting with conduit 112 communicating with the servo casing 44.

Thus, as long as engine speed remains below a value which will permit safe operation of the engine, valve 96 continues to bleed atmospheric air to the servo chamber 52 precluding manifold vacuum from having any effect on the throttle actuating mechanism. When the engine exceeds a given value, centrifugal weight 114 shifts the spindle 100 to close port 102 shutting off the atmospheric bleed causing manifold vacuum to build up in chamber 52 and to move the diaphragm 46 to the right closing the primary throttles 24.

While the moving of the primary throttles 24 toward a closed position tends to reduce the venturi vacuum force in conduit 76, this action has not proven to be positive enough with a hunting action of the secondary throttle resulting. It has been found necessary to provide an additional device to render the governing of the secondary throttle more definite than is otherwise achievable with a power actuated secondary throttle.

To this end, a venting device indicated generally at 120 is provided and communicates through a passage 122 with venturi vacuum conduit 76. Passage 122 includes a vent port 124 open to the atmosphere. Passage 122 is enlarged to provide a bore 126 in which a needle valve 128 is slidably disposed. The tapered end of needle valve 128 is adapted to coat with passage 122 to control the admission of atmospheric pressure into vacuum conduit 76.

The actuation of the needle valve 128 is under the control of a servo mechanism which includes a pair of casing

members 130 and 132 peripherally clamping a diaphragm member 134 therebetween. Casing 132 includes a recess 136 seating one end of a spring 138. The other end of spring 138 biases diaphragm 134 and hence the needle valve 128 to the left to block the passage 122 against the bleeding of atmospheric air thereinto under normal operating conditions.

The chamber 140 defined by casing 130 and diaphragm 134 communicates with the atmosphere through atmospheric port 124. Chamber 142 defined by casing 132 and diaphragm 134 communicates through a passage 144 with a conduit 146. Conduit 146 communicates at its other end with chamber 52 of servo 40. Thus chamber 142 is subjected to the same vacuum control forces as is chamber 52 of servo 40. An orifice 148 is provided in conduit 146 in order to control the rate of actuation of diaphragm 134.

When, as already described in relation to servo 40, the engine speed reaches a sufficiently high value to block off the bleed of atmospheric air through conduit 112 into servo chamber 52, manifold vacuum will act through conduit 146 on diaphragm 134 opening needle valve 128 and venting conduit 76 to atmosphere. Accordingly, the vacuum force acting on secondary throttle servo 66 is eliminated permitting spring 78 to move the secondary throttles 80 toward a closed position. In this way when the engine is tending to overspeed the secondary throttle will be automatically closed without any tendency for the latter to hunt as has been experienced with previous systems.

The carburetor governing system as shown and described is illustrative of the inventive concept involved. It is possible to make various structural modifications in the mechanisms depicted without departing from the scope of the invention as is set forth in the hereinafter appended claims.

I claim:

1. A charge forming device for an internal combustion engine comprising primary and secondary induction passages, a throttle valve in each of said passages, means for opening the primary throttle valve, a servo mechanism operatively connected to the secondary throttle valve, said mechanism including a member biasing the secondary throttle in a closing direction, vacuum conduit means communicating the servo mechanism with the primary induction passage to control the operation of the secondary throttle in accordance with the air flow through the primary induction passage, a governor device, means operatively interconnecting said governor device and the primary throttle valve, said device being adapted to move the primary throttle valve in a closed direction and in so doing to reduce the vacuum in said conduit means, and venting means coating with said vacuum conduit, said governor device being adapted to actuate the venting means to admit atmospheric pressure to the vacuum conduit permitting the biasing member to close the secondary throttle.

2. A charge forming device for an internal combustion engine comprising primary and secondary induction passages, a throttle valve in each of said passages, servo mechanisms for controlling each of said throttles, said primary servo mechanism including means normally biasing the primary throttle in an opening direction, an operator adjustable stop opposing the opening movement of the primary throttle, said secondary servo mechanism including means biasing the secondary throttle in a closing direction, a conduit communicating with said secondary servo for providing a throttle opening force proportional to the quantity of air flow through said device, valve means associated with said conduit for reducing said throttle opening force, and an engine speed responsive governing mechanism for controlling the primary throttle servo and the valve means to cause the throttles to be moved in a closing direction when engine speed exceeds a given value.

3. A charge forming device for an internal combustion

engine comprising primary and secondary induction passages, a throttle valve in each of said passages, means for opening the primary throttle valve, a first servo mechanism operatively connected to the primary throttle valve, a second servo mechanism operatively connected to the secondary throttle valve, vacuum conduit means communicating the second servo mechanism with the primary induction passage to control the operation of the secondary throttle valve in accordance with the air flow through the primary induction passage, a venting mechanism co-acting with said vacuum conduit and adapted to admit atmospheric pressure into said conduit, a third servo mechanism operatively connected to the venting mechanism, means normally biasing said third servo mechanism to prevent the admission of atmospheric pressure into said vacuum conduit, a common passage means interconnecting said first and third servo mechanisms, and a governor device adapted to provide a control pressure proportional to speed, said governor device being operatively interconnected with said common passage means to admit said control pressure to said common passage means to actuate said first and third servo mechanisms and thereby govern the primary and secondary throttle valves.

4. A charge forming device for an internal combustion engine comprising primary and secondary induction passages, a throttle valve in each of said passages, spring means for opening the primary throttle valve, a first servo mechanism operatively connected to the primary throttle valve, a second servo mechanism operatively connected to the secondary throttle valve, vacuum conduit means communicating the second servo mechanism with the primary induction passage to control the operation of the secondary throttle valve in accordance with the air flow through the primary induction passage, a venting mechanism coating with said vacuum conduit and adapted to admit atmospheric pressure into said conduit, a third servo mechanism operatively connected to the venting mechanism, spring means normally biasing said third servo mechanism to prevent the admission of atmospheric pressure into said vacuum conduit, a common passage means interconnecting said first and third servo mechanisms, said

10
15
20

common passage means being in open communication with a source of manifold vacuum, and a governor device for controlling the pressure level of vacuum in the common passage means in accordance with engine speed, said governor device being adapted to raise the vacuum level in the common passage to overcome the primary throttle, and third servo spring means causing the throttles to move in a closing direction when engine speed exceeds a given value.

5. Carburetor governing mechanism including primary and secondary induction passages, throttle valves in each of said passages, a servo device for controlling the secondary throttle, a venturi in the primary induction passage, conduit means communicating the venturi and servo whereby the secondary throttle will be opened by a force proportional to the quantity of primary induction passage air flow, means for bleeding atmospheric pressure into said conduit means, and an engine speed responsive governor for controlling the bleed means.

6. A carburetor governing mechanism including primary and secondary induction passages, throttle valves in each of said passages, a servo device for controlling the secondary throttle, a venturi in the primary induction passage, conduit means communicating the venturi and servo whereby the secondary throttle will be opened by a force proportional to the quantity of primary induction passage air flow, means for bleeding atmospheric pressure into said conduit means, and an engine speed responsive governor for controlling the bleed means, said governor being operably connected to said primary throttle valve whereby the throttle valves will be moved in a closing direction when engine speed exceeds a given value.
